HARRY D. ELLIOTT, OF BEVERLY, MASSACHUSETTS, ASSIGNEE TO UNITED SHOE MACHINERY CORPORATION, OF PATERSON, NEW JERSEY, A CORPORATION OF NEW JERSEY.

BOBBIN-WINDING MACHINE.

Application filed April 23, 1919. Serial No. 292,147.

To all whom it may concern:

Be it known that I, HARRY D. ELLIOTT, a citizen of the United States, residing at Beverly, in the county of Essex and State of Massachusetts, have invented certain new and useful Improvements in Bobbin-Winding Machines; and I do hereby declare the following to be a full, clear, and exact description of the invention, such as will enable others skilled in the art to which it appertains to make and use the same.

This invention relates to bobbin winding machines.

The object of the invention is to improve the construction and mode of operation of machines for winding the bobbins of sewing machine shuttles, and to produce a machine of simple and compact construction by which such bobbins may be quickly and efficiently wound.

With this object in view the features of the invention consist in certain novel and improved constructions, arrangements and combinations of parts hereinafter described and particularly pointed out in the claims the advantages of which will be readily understood and appreciated by those skilled in the art.

The invention is illustrated in the accompanying drawings in its preferred form, and will be readily understood from the drawings taken in connection with the following detailed description of the constructions therein shown.

In the drawings Figure 1 is a plan view of a machine embodying the various features of the invention; Fig. 2 is a view in front elevation, partly in section, of the machine; and Fig. 3 is a view in side elevation of the machine looking from the right.

The machine illustrated in the drawings is provided with a bobbin carrying or winding shaft 2 journaled in a bearing in a supporting arm 4 and having its outer end reduced to receive a bobbin 6 and diametrically slotted or split so as to hold the bobbin frictionally thereon.

The driving mechanism for the winding shaft 2 comprises a shell 8 secured to the inner end of the shaft and a driving disk 10 substantially concentric with and embraced by the shell and provided with a peripheral facing of rubber or other suitable friction material indicated at 12. The driving disk 10 is mounted on the inner end of a driving

shaft 14 journaled in a bearing in a bushing 16 secured in a supporting frame-work 18, and has a driving pulley 20 mounted on its outer end. The peripheral flange of the shell 8 is somewhat larger than the periphery 60 of the driving disk 10. A driving connection is established between the shell 8 and the driving disk 10 by moving the shell in a radial direction or in a plane substantially parallel with its plane of rotation from the 65 position shown in the drawings to bring the peripheral flange of the shell into engagement with the periphery of the driving disk, the shell then being driven frictionally from the disk.

To enable the shell 8 to be moved radially to engage the peripheral flange on the shell with and to disengage the same from the periphery of the driving disk, the supporting arm 4, in which the winding shaft is journaled, is pivoted at its rear end on a stud 22 secured by means of a set screw 24 in the rear end of a bracket 26 the forward end of which is clamped on the bushing 16. In starting the machine the supporting arm 4 70 is lifted, thereby bringing the shell 8 into contact with the driving disk 10 at a point below the driving shaft 14, and upon the release of the supporting arm, the arm and the parts supported thereby are swung downwardly by gravity to disengage the shell 85 from the driving disk. The downward movement of the shell 8 is limited by means of a projection 27 formed on a downwardly extending arm of the bracket 26 and arranged to engage the peripheral flange on the shell. The projection 27 is adapted to support the shell 8 in position out of contact with the driving disk 10, as shown in the drawings.

In the present construction the supporting arm 4 is held in elevated position to maintain the shell 8 in driving contact with the driving disk 10 during the winding of the bobbin by means of a latch. This latch is 100 controlled from the thread wound upon the bobbin so that when a predetermined amount of thread is wound on the bobbin the latch is thrown out of operation allowing the arm and the shell 8 to move downwardly to disengage the shell from the driving disk. A spring is interposed between the latch and the supporting arm 4 which, through its action on the arm, maintains the shell 8 in yielding contact with the driving disk dur- 105 110

ing the winding operation, thereby insuring an effective driving action between the disk and the shell at all times even when the parts become worn by continued use.

5 The devices for controlling the position of the arm 4 comprise a lifting lever 28 pivoted on the stud 22 and provided with a laterally bent projection 30 adapted to engage and support the lower end of a spring 10 32 seated in a recess or pocket in the supporting arm 4, as shown clearly in Fig. 3. The downward movement of the lifting lever 28 relatively to the supporting arm 4 under the action of the spring 32 is limited by 15 means of a pin 34 mounted in the arm and arranged to engage a projection on the lever. The lifting lever is provided with a second laterally bent projection 36 to enable said arm to be lifted readily by the operator.

20 The latch for holding the supporting arm 4 in elevated position is indicated at 38. The latch is pivoted on a stud 40 secured in the downwardly extending arm on the bracket 26, and the upper end of the latch 25 is arranged to engage the under side of the projection 30 on the lifting lever 28 to hold said lever and the supporting arm 4 in their uppermost positions. The latch is acted upon by a coiled spring 42 seated in 30 a pocket in the arm 4, which tends to swing the same rearwardly into acting position. In order to disengage the latch from beneath the projection 30 when the bobbin is full of thread, a latch controlling arm 35 44 is secured to the central portion or hub of the latch and preferably formed integral therewith and is arranged to engage between the flanges of the bobbin so as to contact with the thread as it is wound on the 40 bobbin.

When the machine is idle the parts are located substantially in the positions shown in the drawings, the latch 38 being disengaged from beneath the projection 30 on 45 the lifting lever 28, and the peripheral flange on the shell 8 resting on the projection 27.

In starting the machine the operator grasps the lateral projection 36 on the lifting 50 lever 28 and lifts the same thereby through the spring 32, lifting the supporting arm 4 and carrying the shell 8 into contact with the periphery of the driving disk 10 to start the rotation of the winding shaft. As the 55 lateral projection 30 on the lifting lever 28 is carried above the upper end of the latch 38, the latch is swung rearwardly beneath said projection by the action of the spring 42 and the arm 44 is swung upwardly between the flanges of the bobbin into position 60 to engage the thread as it is wound thereon. During the winding operation the shell 8 is maintained in yielding contact with the periphery of the driving disk 10 through 65 the action of the spring 32. As the amount

of thread on the bobbin increases the latch controlling arm 44 is swung downwardly through the engagement of the thread therewith, and when a predetermined amount of thread has been wound on the bobbin the 70 latch 38 is disengaged from beneath the lateral projection 30 allowing the lifting lever 28, the supporting arm 4 and the shell 8 to descend under the action of gravity until the shell engages the projection 27, 75 thereby disengaging the shell from driving contact with the driving disk. The projection 27 acts as a brake on the shell 8 to stop the rotation thereof and of the winding shaft.

Having explained the nature and object of the invention, and having specifically described a machine embodying the invention in its preferred form, what is claimed is:

1. A bobbin winding machine having, in 85 combination, a winding shaft, driving connections therefor comprising a rotary disk member, a rotary shell member closely embracing and substantially concentric with said disk member, a carrier for supporting 90 one of said members movable to carry the latter member radially in a definite path into and out of driving contact with the other member, and means for controlling the position of the movable member from the 95 mass of thread on the winding shaft.

2. A bobbin winding machine having, in combination, a winding shaft, driving connections therefor comprising a rotary disk member, a rotary shell member embracing 100 said disk member, a carrier for supporting one of said members movable to carry the latter member radially in a definite path into and out of driving contact with the other member, and means acting on the 105 carrier for holding the movable member yieldingly in driving contact with the other member.

3. A bobbin winding machine having, in combination, a rotary disk member, a rotary 110 shell member embracing said disk member, a winding shaft secured to one of said members, a carrier for the shaft and the latter member mounted for movement to move the latter member radially into and out of 115 driving contact with the other member, and means for controlling the position of the carrier.

4. A bobbin winding machine having, in combination, a winding shaft, driving connections therefor comprising a rotary disk member and a rotary shell member, one 120 of which is arranged to be moved upwardly from a certain position to carry the same into driving contact with the other member and to be moved downwardly by gravity to carry the same out of driving contact with the other member, a movable carrier for the movable member, means for holding said members yieldingly in driving 125 contact with the other member and to be moved downwardly by gravity to carry the same out of driving contact with the other member, a movable carrier for the movable member, means for holding said members yieldingly in driving 130 contact with the other member.

contact, and means for limiting the downward movement of the movable member under the action of gravity to hold the same in position out of driving contact with the 5 other member.

5. A bobbin winding machine having, in combination, a winding shaft, driving connections therefor comprising a rotary disk member and a rotary shell member, one of 10 which is arranged to be moved in one direction to carry the same into driving contact with the other member and to be moved in the other direction to carry the same out of driving contact with the other member, a 15 movable carrier for the movable member, and an abutment for engagement with the movable member to limit the movement thereof in the latter direction acting as a brake to arrest the rotation of said member.

20 6. A bobbin winding machine having, in combination, a winding shaft, driving connections therefor comprising a rotary disk member, a rotary shell member closely embracing and substantially concentric with 25 said disk member, means for supporting one of said members for movement radially to carry the same into and out of driving contact with the other member, a latch for holding the movable member in driving contact 30 with the other member, and means for controlling the latch.

7. A bobbin winding machine having, in combination, a winding shaft, driving connections therefor comprising a rotary disk 35 member, a rotary shell member embracing said disk member, one of which is movable radially to carry the same into and out of driving contact with the other member, a pivoted carrier for the movable member, a 40 lever pivoted coaxially with the carrier, a spring interposed between the carrier and the lever, a latch for engaging the lever to hold the carrier in position with the disk and shell members in driving contact, and 45 means for controlling the latch.

8. A bobbin winding machine having, in combination, a winding shaft, driving connections therefor comprising a rotary disk member and a rotary shell member embracing 50 said disk member and mounted to rotate upon an axis substantially parallel with the axis of the disk member, one of which is mounted for movement radially to carry the same into and out of driving contact with 55 the other member, a carrier for the movable member pivoted on an axis substantially parallel with the axis of rotation thereof, a lever pivoted coaxially with the carrier, a

spring interposed between the lever and the carrier, a latch lever pivoted on an axis substantially parallel with the axis of the latter lever and having an arm for engaging the latter lever to hold the carrier in position with the disk and shell members in driving contact, and a second arm for engaging the 65 thread wound on the bobbin.

9. A bobbin winding machine, having, in combination, a frame, a bushing secured in the frame, a driving shaft journaled in the bushing, a rotary disk member and a rotary 70 shell member one of which is secured to said driving shaft, a bracket secured to said bushing, a winding shaft secured to the other of said members, a carrier for the latter member and the winding shaft mounted on said 75 bracket for movement to carry the latter member into and out of driving engagement with the other member, and devices for controlling the position of the carrier mounted on the bracket.

80 10. A bobbin winding machine having, in combination, a winding shaft, driving connections therefor comprising a rotary disk member, a rotary shell member closely embracing and substantially concentric with 85 said disk member, a pivoted carrier for supporting one of said members for movement radially to carry the same into and out of driving contact with the other member, and means for controlling the swinging movement of the carrier.

90 11. A bobbin winding machine having, in combination, a winding shaft, driving connections therefor comprising a rotary disk member, a rotary shell member closely embracing and substantially concentric with 95 said disk member, a carrier on which one of said members is journaled mounted for movement radially to carry the latter member into and out of driving contact with the 100 other member, and means for controlling the position of the carrier.

105 12. A bobbin winding machine having, in combination, a winding shaft, driving connections therefor comprising rotary driving and driven members, a carrier upon which one of said members is journaled mounted for movement to carry the same into and out of driving contact with the other member, a latch acting on the carrier, a spring intermediate the latch and the carrier to hold the member which is journaled on the carrier in yielding engagement with the other member, and means for controlling the latch.

110 HARRY D. ELLIOTT.
